TOOL FOR EXPANDING AND CONTRACTING
PIPE CLAMPING COLLARS

Dwight E. Hammon, Virgilia, Calif.

Application March 24, 1934, Serial No. 717,191

5 Claims. (Cl. 81—3)

This invention relates to tools to be used in connection with the coupling collars for corrugated culverts and similar pipes.

Culverts of this character are formed with circumferential corrugations and the collars, which are split lengthwise and provided with upstanding flanges along the split edges adapted to be bolted together, are also corrugated to fit the corrugations in the culverts. As a result of this construction, a collar when once secured in place about a culvert cannot be merely loosened and spread from place but must be first spread to clear the cooperating corrugations and allow of the separation of the culvert sections. When the collar is once spread to receive a section therein, its ends must then be drawn together a considerable amount before the holding bolts can be applied.

The principal object of my invention therefore is to provide a tool unit by means of which the ends of the collar may be easily and quickly spread or drawn together as the case may demand. Operations incident to assembling and connecting culvert sections of this character are therefore greatly facilitated and expedited over what is now the case.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Figure 1 is a perspective view of the tool unit as engaged with a collar and in position to spread the ends of the same.

Figure 2 is a fragmentary enlarged front view of the tool showing the position of the spreading bar relative thereto at the start of a spreading operation.

Figure 3 is a side view of the tool unit as engaged with a collar and in position to draw the ends of the collar together.

Referring now more particularly to the characters of reference on the drawing, the collar with which the tool is to be used comprises a rectangularly split band 1 having circular corrugations as at 2 and provided along its split edges with outwardly projecting angle iron flanges 3 having spaced matching bolt holes 4.

The tool comprises a pair of similar opposed

legs 5 hinged together at one end as at 6 for opening and closing movement relative to each other. The legs at the free end are normally spread apart some distance and are formed with extensions 7 disposed circumferentially parallel to each other and at right angles to the legs. Stub pins 8 project from the opposite sides of the extensions intermediate their ends and are adapted to freely project through an opposed pair of the bolt holes in the collar flanges.

Adjacent their hinged end the legs are partially bowed relative to each other, the adjacent faces of the legs then converging toward each other at an acute angle as shown at B to finally form a relatively restricted passage between the legs as indicated at B. Beyond the passage the legs then diverge toward their extension end, and below said restricted passage the legs are connected by a light chain 9 or similar flexible element to limit the possible amount of spread. The legs are arranged relative to each other and to the size of a collar to be manipulated so that when the extensions 7 are placed between the flanges 3 and the collar is in a contracted position, said passage B is very narrow.

Means to spread the legs when the tool is in the above position and forming a necessary part of the tool unit is provided in the form of a special crowbar 10 of suitable length. This bar near its lower end is provided with a pair of spaced and parallel cross rods 11. Between the rods and near the upper one the opposite sides of the bar are cut with wide flat grooves 12 disposed in transversely converging relation to each other, as shown in Figure 2. The width of the grooves is greater than the thickness of the legs 5 and the angular setting of the same approximates that of the sides A of the legs when the passage B is most restricted. The grooves are positioned relative to the upper cross rod 11 so that when the bar 10 is projected between the legs above the passage and is held with the upper rod against one face of the same, said grooves lie in the transverse plane of the legs so that they are in position to engage the adjacent side walls of the passage. When the crowbar is thus mounted in position relative to the legs and is disposed at a forward acute angle thereto, as shown in Figure 1, a combined longitudinal and downward pressure on the bar will cause the upper rod 11 to slide down on the legs, and the grooves will engage between and separate the legs at the narrow passage B. The spread thus imparted to the legs is sufficient at the flange engaging end of the same to allow the collar to be

withdrawn from the culvert or another section of culvert to be inserted in the collar. The crow-bar is placed through the tool from the side opposite the extensions 7 as shown so that the downward push of the bar against the tool will cause the extensions to bear against the culvert so that the said tool cannot get out of its proper vertical position.

When it is desired to contract the collar about 10 the culvert the tool is turned to extend between and across the flanges 3, with the extensions 7 projecting downwardly and with their lower ends engaging under the base of one of the flanges 3 between the corrugation of the collar as indicated in Figure 3. To enable the extension to have a non-slipping hold, their ends are turned up somewhat, as shown at 13.

The crowbar 10 is inserted between the legs at their hinged end and its lower end is engaged 20 under the base of the adjacent flange 3. The bar is flattened at its lower end and is also turned up slightly as at 14 to provide a better grip with the flange. Upon pulling the bar in a direction transversely of the collar and using the lower end 25 of the bar as a fulcrum it will be seen that the flanges 3 will be drawn toward each other to any necessary extent.

From the foregoing description it will be readily seen that I have produced such a device as 30 substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by 40 Letters Patent is:

1. A tool to spread a split collar, said collar having upstanding flanges along its split edges, said tool comprising a pair of legs hinged together at one end, means at the other end of the legs 45 for engagement with the adjacent faces of the flanges, the adjacent faces of the legs being bowed apart at their hinged end and then converging toward each other at an acute angle to leave a relatively narrow passage therebetween 50 intermediate their ends, and a bar insertible between the bowed portion of the legs and adapted to be depressed into spreading engagement with said converging faces of the legs.

2. A tool to spread a split collar, said collar 55 having upstanding flanges along its split edges,

said tool comprising a pair of legs hinged together at one end, and adapted at the other end for engagement with the adjacent faces of the flanges, the adjacent faces of the legs being bowed apart at their hinged end and then converging toward each other at an acute angle to leave a relatively narrow passage therebetween intermediate their ends, a bar insertible between the bowed portion of the legs, said bar being formed with opposed grooves disposed in transversely 10 converging relation to each other at an angle approximately that of the angle of convergence of the leg faces, and a cross element on the bar to engage the legs on one side and positioned so that the grooves will then align with said adjacent faces of the legs. 15

3. A tool to spread a split collar, said collar having upstanding flanges along its split edges and opposed bolt holes in the flanges, said tool comprising a pair of leg members hinged together 20 at one end and adapted at the other end to engage the adjacent faces of the flanges, pins projecting laterally from the opposed faces of the members for engagement with the bolt holes, and means to spread the legs. 25

4. A tool to contract a split collar, said collar having upstanding flanges along its split edges, said tool comprising a pair of legs hinged together at one end, parallel extensions on the opposite ends of the legs disposed at right angles thereto, the legs being adapted to be disposed so as to extend across and above the flanges with the extensions depending for engagement with the outside of one flange at the base, and a bar insertible between the legs at their hinged end and adapted 30 at one end to extend outside the other flange and engage the same at the base. 35

5. A tool to selectively spread or contract a split collar, said collar having upstanding flanges along its split edges, said tool comprising a pair of legs hinged together at one end, parallel extensions on the opposite ends of the legs disposed substantially at right angles thereto, said extensions being adapted to engage the adjacent faces of the collar flanges when the legs project outwardly 45 from the collar and to depend for engagement with the outside of one flange when the legs extend above and across the flanges, and means removably insertible between the legs to spread the same when the legs are in the first named position, and to engage the opposite flange and pull against the hinged end of the legs when the latter occupy the second named position. 50
